ELECTRICAL MUSICAL INSTRUMENT

Daniel J. Tomcik, Buchanan, Mich., assignor to Electro-Voice, Incorporated, Buchanan, Mich., a corporation of Indiana

Filed Mar. 21, 1961, Ser. No. 97,354
13 Claims. (Cl. 84—1.17)

The present invention relates generally to electrical musical instruments, and more particularly to electrical chord organs.

Most organs have at least two keyboards or manuals. The first manual of an electrical organ has a first group of keys coupled to a first group of electrical tone generators which are provided with a first group of voicing filters. The second manual has a second group of keys which are coupled to a second group of electrical tone generators which are provided with a second group of voicing filters. Such an instrument permits the simultaneous production of musical notes from both groups of keys of the keyboard with different voices from the two groups of keys. The two keyboards may be mounted in alignment to form a "split keyboard," that is, a keyboard which has no divider between the manuals and the manuals are on the same plane, as disclosed by Langer in United States Patent No. 2,458,178.

In order to reduce the number of keys of the keyboard, and also to simplify the requirements for playing the instrument, some electrical musical instruments utilize only a single keyboard and a plurality of chord buttons. The single keyboard is played by the right hand and actuates switches controlling electrical tone generators to produce the melody of the music. Each button actuates a plurality of switches which energize a plurality of electrical tone generators to produce a chord, so that actuation of a single button simultaneously produces all of the musical notes of a chord. A chord organ of this type has limited usefulness, since regular piano or organ music cannot wholly be interpreted on the instrument. Vamps, contrameadow, melody and other piano and organ techniques played with the left hand cannot be executed with such a chord organ. Further, there is a limited use for such an organ in the education of an artist.

It is an object of the present invention to provide an electrical musical instrument which may be, at the option of the artist, played as a chord organ or as a two manual organ, and particularly a split keyboard two manual organ.

It is a further object of the present invention to provide an electrical musical instrument of the keyboard type with a novel and improved keyboard switch mechanism.

It will be recognized upon further consideration of the present invention that it is a general object of the invention to provide an electrical organ which is both more versatile than existing instruments and less costly than those instruments which are comparable in a generic sense. These objects and advantages of the present invention will be more fully appreciated upon a further consideration of this disclosure, particularly when viewed in the light of the drawings, in which:

FIGURE 1 is a schematic block diagram illustrating an electrical organ constructed according to the teachings of the present invention;

FIGURE 2 is a schematic electrical circuit diagram of a portion of the electrical organ illustrated in block diagram in FIGURE 1;

FIGURE 3 is a fragmentary plan view of the underside of the keyboard of the musical instrument;

FIGURE 4 is a sectional view of the keyboard taken along the line 4—4 of FIGURE 3; and

FIGURE 5 is an elevational view of one of the contact

2

members of the keyboard illustrated in FIGURES 3 and 4.

The electrical organ illustrated in the figures is a preferred construction of the present invention, and the present invention can be practised with many other constructions. The electrical organ illustrated in FIGURE 1 has an oscillator assembly 10 which contains an electrical tone generator or oscillator with the frequency of each of the musical notes which the organ is capable of producing, with the exception of notes at the lowest frequencies of the organ. This low frequency group of notes are produced by a frequency divider 12 in the form of a multivibrator which is connected to the low frequency oscillators or generators of the oscillator assembly 10 through a pedal clavier 14. The pedal clavier 14 of one particular construction described throughout this application has 13 pedals. The 13 lowest frequency tone generators of the oscillator 10 are connected through the pedal clavier 14 to the multivibrator 12.

These 13 tone generators are a part of a first group of tone generators which are connected to a first manual or keyboard 16, and each of the keys of this manual 16 is provided with a gang of switches 17 mechanically coupled thereto. One of the switches 18 of each gang 17 is utilized to produce the fundamental frequency of the tone generator of the oscillator assembly 10. A second switch 20 of the gang 17 is utilized to connect this same tone generator with the input of the multivibrator 12 to produce an electrical signal having a frequency one octave below that of the fundamental tone generator, and at least one chord addition switch 22 is used to connect one of the other tone generators into the circuit to produce the desired chord. As will be clear from a description of FIGURE 2, the bass switches 29 which are utilized to produce the lowest octave of frequencies are connected through a chord switch 24 to the multivibrator, and the pedal clavier 14 is also connected through this chord switch 24. In like manner, the chord addition switches 22 are connected through the chord switch 24.

The outputs of the multivibrator 12 and manual 16 are connected to the input of an accompaniment filter 26 which permits the selection of one of a plurality of voices for the low frequency or left hand notes of the organ. The output of the accompaniment filter 26 is connected to a preamplifier 28, and the preamplifier is connected to a power amplifier 30. A loudspeaker 32 is connected to the output of the power amplifier. A swell shoe 34 is also connected to the preamplifier 28 in order to manually modulate the amplitude of the organ tones produced.

The oscillator assembly 10 also has a second and higher frequency group of tone generators, and these tone generators of the second group are connected to a second manual 36. The manual 36 is connected through a second voicing filter 38 to the input of the preamplifier 38. The organ also has a vibrato generator 40 which is connected to the oscillator assembly 10 to modulate the amplitude of the tone generators at a vibrato rate.

From FIGURE 2, the first group of tone generators of the tone generator assembly can be identified as the tone generators for the notes C₁, C₁#, D₁, D₁#, E₁, F₁, F₁#, G₁, G₁#, A₁, A₁#, B₁, C₂, C₂#, D₂, D₂#, and E₂, these outputs being indicated within the bracket 42. The second group of tone generators comprise all of the other tone generators which are the immediately higher frequency notes of the evenly tempered scale, and these have been designated within the bracket 44. All of the outputs of the oscillator assembly 10 are connected to a multiconductor cable 46 which connects each of the outputs of the oscillator assembly 10 to its associated switches of the first manual 16, the second manual 36 or the pedal clavier 14. For example, the lowest frequency tone generator of the oscillator assembly 10 has a frequency corresponding to the

note C_1 which is 65.4 cycles per second, and the multiconductor cable 46 connects this output terminal to the first switch 18 of the key for playing the note C_1 , designated 48a in FIGURE 2. The multiconductor cable 46 also connects the output for the tone generator producing the note C_1 to the switch 52a associated with the lowest frequency pedal of the pedal clavier 14 so that the note C_0 one octave below this note may be produced through the pedal clavier and the multivibrator 12. It is also clear from FIGURE 2 that each of the keys has two chord addition switches 22a and 22b ganged with the switches 18 and 20, and that the multiconductor cable 46 connects these switches to the appropriate outputs of the oscillator assembly 10 to produce the desired chords.

The chord switch 24 actually includes three separate sections 50a, 50b and 50c which are ganged together. Each of the sections of the chord switch 24 has two stationary contacts and a movable contact. The movable contact of the section 50a of the chord switch 24 is connected to each of the stationary contacts of the switches 22a and 22b which are associated with the keys of the first manual. One of the stationary contacts of the section 50a, which has been designated "on" is connected to each of the stationary contacts of the switches 18 associated with the keys of the first manual and also to the input of the accompaniment filter 26. The other stationary contact of the section 50a, designated "off" is connected to ground. The stationary contact of section 50b which corresponds to the first stationary contact of the section 50a is connected to each of the stationary contacts of the switches 20 associated with the keys of the first manual. In addition, this stationary contact is also designated "on" and connected to the second stationary contact of the third section 50c of the switch 24 which is designated "off." The movable contact of the second section 50b is connected to the input of the multivibrator 12. The movable contact of the third section 50c of the chord switch 24 is connected to ground. The second contact of the section 50b is connected to the movable contact of the first switch 52a of the pedal clavier 14.

It is to be noted that the second manual 36 has keys which are associated with each of the tone generators of the second group 44, and it also has keys which are associated with the twelve highest frequency tone generators of the first group 42. In this manner, the melody may be played on the second manual including the twelve highest frequency notes of the first group of tone generators. Obviously, the invention may be practiced with or without this overlapping feature and with more or less overlapping than has been here provided.

If it is desired to use the chord feature of the organ shown in FIGURES 1 and 2, the chord switch 22 is put in the "on" position, as illustrated in FIGURE 2. It is to be noted that the position of the chord switch 24 does not affect the connection of the stationary contacts of the switches 18 associated with the keys of the first manual with the input of the accompaniment filter 26. It does, however, connect the stationary contacts of each of the switches 22a and 22b associated with the keys of the first manual to the input of the accompaniment filter 26 through the first section 50a of the chord switch 24. In addition, the stationary contacts of the switches 20 are connected through the section 50b of the chord switch 24 to the input of the multivibrator 12 to produce a note one octave below the fundamental frequency of the note played. In the "on" position the third section 50c of the chord switch 24 has no effect. However, in the "off" position, the third section 50c of the chord switch 24 connects the stationary contacts of the switches 20 to ground. In the "off" position, the second section 50b of the chord switch 24 connects the input of the multivibrator 12 to the pedal clavier 14.

It is to be noted that the pedal clavier 14 has a switch 52a, 52b, 52c, etc. associated with each of the pedals thereof. Each of these switches has a stationary contact

which is connected through the multiconductor cable 46 to one of the tone generators of the first group of tone generators of the oscillator assembly 10. The first switch 52a of the pedal clavier 14 has a movable contact which is connected, as stated above, to the "off" stationary contact of the section 50b of the chord switch 24, and each of the switches also has a second stationary contact. The second stationary contact of the switch 52a is connected to the movable contact of the switch 52b, and the second stationary contact of the switch 52b is connected to the movable contact of the switch 52c, and the other switches of the pedal clavier are also connected in the same manner. The switches are normally in the position in which the movable contact abuts the second stationary contact, as shown in FIGURE 2. As a result, when more than one pedal of the pedal clavier 14 is depressed, the lowest tone represented by the depressed pedals alone is produced.

The specific construction of the tone generators has not been illustrated, since there are many well known musical instrument tone generators. A particularly suitable tone generator for use in the present electrical organ is that disclosed in the patent application of Daniel J. Tomcik entitled "Oscillator and Frequency Divider Assembly," Serial No. 75,270, filed December 12, 1960.

It is to be noted that each of the keys of the second manual has but a single switch 53 associated therewith, and the stationary contact of each of the switches 53 is connected to the input of the voicing filters 38. The movable contact of each of the switches 53 is also connected to the multiconductor cable 46 through a resistor 54. In like manner, each of the switches 18, 20, 22a, and 22b associated with the keys of the first manual are connected to the multiconductor cable 46 through a resistor 54.

FIGURES 3, 4 and 5 illustrate the construction of the switches 18, 20, 22a, and 22b, associated with the keys of the first manual 16. The keys 48 are mounted on a support bracket 56 which extends the entire length of the first and second manuals 16 and 36. The support bracket 56 has a plate 58 and depending portions at opposite ends of the plate designated 60 and 62 which mount the support bracket 56 to a cabinet. The switches 18, 20, 22a, and 22b are mounted in an assembly 64 which is disposed between the portions 60 and 62 and which is secured to the underside of the plate 58 by a pair of angular members 66. Each key 48 is pivotally mounted adjacent to one end on a notched member 68 which extends from the plate 68 adjacent to the portion 62 of the bracket 56, and a spring 70 extends between the bracket 56 and an extension portion 72 of each key 48 to spring bias the key in a direction away from the switch assembly 64. A guide member 74 mounted on the bracket 56 adjacent to the portion 60 also extends into an indentation 75 of each key 48 to maintain it in alignment.

The switch assembly 64 itself comprises a plurality of sheets 76 of electrically insulating material, such as fiberboard or Bakelite. In the particular construction, 13 sheets 76 are employed, and these sheets are mounted in a stack to form a laminated structure by means of a plurality of bolts 78 which extend through the sheets, and two of the bolts 78 also secure the stack of sheets to the mounting brackets 66. Each of the sheets 76 is provided with a first row of rectangular openings 80 of equal size, and a second row of rectangular openings 82 also of equal size. In this manner, each sheet is provided with a longitudinal rib 84 between the openings 80 and 82 and a lateral rib 86 between adjacent openings 80 and adjacent openings 82. In effect, the openings 80 also form a rib 88 on the side of the opening opposite the longitudinal rib 84, and the openings 82 form a third lateral rib 90 on the side thereof opposite the first lateral rib 84. The sheets 76 are assembled with the openings 80 and 82 in alignment, so that the laminated structure which results from assembly of the sheets 76 also has openings

which extend therethrough corresponding to the openings 80 and 82.

The second and third sheets designated 76a and 76b, have confronting grooves 92 which are disposed parallel to the second longitudinal rib 88 and adjacent thereto, and a first bar 94 of electrically conducting material is clamped within the grooves 92 of the sheets 76a and 76b. In like manner, the fifth and sixth sheets designated 76c and 76d, have confronting grooves 92 which are parallel to the second longitudinal rib 88 and a second bar 96 of electrically conducting material is clamped within these grooves 92. Also, the eight and ninth sheets, designated 76e and 76f, are provided with confronting grooves parallel to the second longitudinal rib 88, and a third bar 98 of electrically conducting material is disposed within these grooves 92. The electrically conducting bars 94, 96, and 98, are disposed in a common plane normal to the planes of the sheets 76.

An elongated contact member 100 is clamped at one end between the portions of the first sheet, designated 76g, and the second sheet 76a, used to form the longitudinal rib 84, and the contact member extends from the longitudinal rib 84 normal to the bar 94 and terminates in confrontation with the bar 94. The first sheet 76g is provided with two spaced bores 102 along an axis normal to the bar 94 which accommodate two spaced prongs 104 which extend from the contact member 100 and maintain the contact member normal to the bar 94. As is clear from FIGURE 5, the prongs 104 are formed by bending cutouts in a flat elongated strip 106 of electrically conducting resilient material. The ends of this strip 106 opposite the prongs 104, carries a circular prong 108 of material of higher resilience than the strip 106. It is thus clear that while the strip 106 is capable of bending upon actuation, the outwardly extending prong 108 is capable of substantially greater bending. The strip 106 also has an aperture 110 located therein between the prongs 104 and the end of the strip.

A second contact member 112 is mounted between the fourth sheet 76h and fifth sheet 76c. This second contact member is similar in construction to the first contact member 100, and the outwardly extending prong 108 thereof confronts the second bar 96. In like manner, a third electrically conducting contact member 114 is mounted between the seventh sheet 76i and eighth sheet 76e. The third contact member 114 also has an outwardly extending prong 108 which confronts the third bar 98. The outwardly extending prongs 108 of the first contact member 100, second contact member 112, and third contact member 114, all confront the bars 94, 96 or 98, respectively, on the side of the bars confronting the first sheet 76g so that movement of the contact members in a direction away from the first sheet 76g will cause the contact members to abut the bars.

A fourth contact member 116 is mounted between the tenth sheet 76j and the eleventh sheet 76k, and it also is of similar construction to the contact members 100, 112, and 114. There is one major difference between these contact members, and that difference concerns the existence and size of the aperture 110. The contact member 116 has no aperture, while the contact member 114 has but a small aperture, the contact member 112 a larger aperture, and the contact member 100 has the largest aperture. An actuator pin 118 extends through the apertures 110 in the contact members 100, 112, and 114, and has an end portion 119 which terminates in abutment with the contact member 116. The actuator pin also has a portion 120 disposed between the second and third contact members 112 and 114, with a greater diameter than the aperture in the third contact member, but smaller than aperture in the second contact member. In like manner, the actuator pin 118 has a cylindrical portion 122 located between the first and second contact members 100 and 112 which has a diameter bigger than the aperture in the contact member 112 and smaller than the

aperture in the contact member 100. Also, the actuator pin has a portion 124 of larger diameter than the aperture 110 in the first contact member 100 which abuts this contact member. It is thus clear that a force applied to this latter portion 124 will result in movement of all four of the contact members.

The prong 108 of the fourth contact member 116 is disposed between two contact plates 126 and 128. The contact plates are provided with rectangular indentations 130, and the rectangular indentation 130 of the contact plate 128 is disposed about the first rib 88 of the tenth sheet 76j. In like manner, the rectangular indentation 130 of the contact plate 126 is disposed about the first rib 88 of the twelfth plate 76l. Both of the plates 126 and 128 extend outwardly from the laminated structure to form contact terminals 132. In this manner, the fourth contact member 116 makes contact with one of the contact plates 126 or 128 only.

Terminal strips 134 are also disposed between the sheets 76 in the third rib 90, these terminal strips 134 being aligned with the contact members. The terminal strips terminate at their ends adjacent to the contact strips in flanges 136 which are normal to the strips 134, and the confronting ends of the contact strips also terminate in flanges 138. An electrical component, such as the resistor 54, is connected between the flange 136 of the terminal strip 134 and the flange 138 of the contact strip 106. It is to be noted that the terminal strips 134 are also provided with two outwardly extending prongs 140 which mate in bores in the third rib 90 of the assembly of sheets 76.

It is to be noted that each of the keys of the first manual 16 actuates the four contact strips 100, 112, 114, and 116 of the switch assembly 64. The switch 18 is formed by the contact strip 100 and bar 94. In like manner, the switch 20 is formed by the contact strip 116 and the contact plates 126 and 128. The switches 22a are formed by the contact strips 112 and conducting bar 96, while the switches 22b are formed by the contact strips 114 and the bar 98. It is also to be noted that the switches 53 of the second manual 36 are constructed in essentially the same manner as the switches 18 which are described in FIGURES 3 and 4, except that only one contact member is employed, and this contact member corresponds to the contact member 116 of the switch assembly 64 in that the aperture 110 is omitted. It is, of course, unnecessary in the switches of the second manual to utilize more than three sheets 76 of insulating material of a single conducting rod corresponding to the rod 94.

Each actuator pin 124 is aligned with an actuator key 142 which is mounted on one of the keys 48. When a key 48 of the first manual is depressed, it causes the actuator pin to move the four contact members 100, 112, 114 and 116 and effect switching action. The spring 70 returns the key 48 to its rest position.

It will be recognized that the switch assembly 64 here disclosed is adapted for mass production techniques, and effectively provides gang switching in a very small area. In addition, it is to be noted that when the chord switch 24 is in the "off" position, the switching mechanism is effective to play the fundamental note, for example, the switch 48a will then play the note C₁. When the chord switch 24 is in the "on" position, this same key 48a plays a chord in which the note C₁ is fundamental, that is, it plays the chord C₁, E₁, G₁ and in addition, adds the bass note C₀. The other keys of the first manual 16 operate in the same manner. It is thus clear that an electrical musical instrument has been provided in which the low frequency or left hand manual may be used at the option of the artist to play chords or fundamental notes in the same manner of either of split keyboard organs or a chord organ.

From the foregoing disclosure, those skilled in the art will readily devise many and additional uses for the

present invention, and will clearly foresee many additional advantages of the structures herein set forth. It is therefore intended that the scope of the present invention be not limited by the foregoing disclosure, but rather only by the appended claims.

The invention claimed is:

1. An electrical organ comprising, in combination, a plurality of electrical generators having frequencies in the audio range respectively corresponding to successive notes of a musical scale, an electroacoustic transducer having an input for electrical signals, a first keyboard and a second keyboard disposed in a common plane adjacent to each other, a first electrical switch mechanically coupled to each key of the first keyboard and the second keyboard, each of the first switches being normally open and electrically connected between the input of the electroacoustic transducer and one of the tone generators, a second switch mechanically ganged to each first switch associated with a key of the first keyboard, the second switch being normally open and having two terminals, a manually actuatable third electrical switch having a first terminal connected to the input of the electroacoustic transducer and a second terminal connected to one terminal of each second switch, the other terminal of each second switch being electrically connected to two tone generators different than the tone generator connected to the first switch associated with the same key of the first keyboard, said three tone generators associated with each key of the first keyboard having frequencies corresponding to the notes of a musical chord.

2. An electrical organ comprising a plurality of audio frequency tone generators having output frequencies respectively corresponding to successive notes of a musical scale, an electroacoustic transducer having an input for electrical signals, a first keyboard and a second keyboard, a first electrical switch mechanically coupled to each key of the first and second keyboards, each of said first switches being normally open and electrically connected between the input of the electroacoustic transducer and one of the tone generators, characterized by the improved construction wherein a second switch is mechanically ganged to each first switch associated with a key of the first keyboard, each of said second switches being normally open and having two terminals, and a manually actuatable electrical third switch having a first terminal connected to the input of the electroacoustic transducer and a second terminal connected to one terminal of each of the second switches, the second terminal of each second switch associated with a key of the first keyboard being electrically connected to a tone generator having a frequency constituting with the tone generator connected to the first switch associated with said key the notes of a musical chord.

3. An electrical organ comprising the elements of claim 2 wherein the first and second switches associated with each key of the first keyboard are disposed in a common assembly comprising a plurality of sheets of electrically insulating material, means for assembling said sheets into a laminated structure, said laminated structure having an opening extending therethrough, a first electrically conducting bar disposed between two abutting sheets and a second electrically conducting bar disposed between another two abutting sheets, said bars being parallel to each other and extending through the opening in the laminated structure, a first elongated contact member mounted at one end between two abutting sheets generally normal to the first bar and extending to confront the first bar at the other end, a second elongated contact member mounted at one end between another two sheets normal to the second bar and extending to confront the second bar at the other end, the first and second contact members being of resilient electrically conducting material and constituting the second terminal of each switch, the electrically conducting bar constituting the first terminal of each switch.

4. An electrical organ comprising a plurality of audio frequency tone generators having output frequencies respectively corresponding to successive notes of a musical scale, an electroacoustic transducer having an input for electrical signals, a first keyboard and a second keyboard, a first electrical switch mechanically coupled to each key of the first and second keyboards, each of said first switches being normally open and electrically connected between the input of the electroacoustic transducer and one of the tone generators, characterized by the improved construction wherein a second and a third switch are mechanically ganged to each first switch associated with a key of the first keyboard, said second and third switches being normally open and having two terminals, a manually actuatable electrical switch assembly including a first and second section mechanically ganged together, the first section having a first terminal connected to the input of the electroacoustic transducer and a second terminal connected to one terminal of each second switch, the other terminal of each second switch being electrically connected to a tone generator different than the tone generator connected to the first switch associated with the same key of the first keyboard and forming a chord with the tone generated by the generator connected to the first switch of said key, a frequency divider having an output terminal coupled to the electroacoustic transducer and an input terminal connected to one terminal of the second section of the manually actuatable electrical switch assembly, the other terminal of said second section being electrically connected to one terminal of each of the third switches, the other terminal of each of the third switches being electrically connected to the same tone generator as the first switch.

5. An electrical organ comprising the elements of claim 4 wherein the second section of the manually operable switch assembly has a pair of stationary contacts and a movable contact, the multivibrator being electrically connected to the movable contact and one of the stationary contacts being electrically connected to the one terminal of each of the third switches, in combination with a pedal clavier having a plurality of pedals and an electrical switch mechanically associated with each pedal, each switch of the pedal clavier having a first terminal electrically connected to one of the tone generators and a second terminal electrically connected to the other stationary contact of the second section of the manually operable switch assembly.

6. An electrical organ comprising a plurality of audio frequency tone generators having output frequencies respectively corresponding to the successive notes of a musical scale, an electroacoustic transducer having an input for electrical signals, a first keyboard and a second keyboard, a first electrical switch mechanically coupled to each key of the first and second keyboards, each of said first switches being normally open and electrically connected between the input of the electroacoustic transducer and one of the tone generators, a second electrical switch mechanically coupled to each key of the first keyboard including a plurality of sheets of insulating material, said sheets being secured together to form a laminated structure and said laminated structure having an opening therethrough, an electrically conducting bar disposed between the two sheets of insulating material and extending across the opening, an elongated contact member having one end mounted between adjacent sheets of insulating material and the other end confronting the conducting bar, said contact member being constructed of resilient electrically conducting material, and an actuating member movably mounted to abut the contact member between the two ends thereof and move the contact member relative to the electrically conducting bar, said second switches being normally open, and a manually actuatable electrical switch having a first terminal connected to the input of the electroacoustic transducer and a second terminal connected to the electrically conducting bar of

each of the second switches, the contact member of each of the second switches being connected to a different tone generator than the tone generator connected to the first switch associated with the same key of the first keyboard.

7. An electrical organ comprising the elements of claim 6 wherein the laminated structure of insulating sheets is provided with a second opening adjacent to the mounted end of the contact member, said mounted end of the contact member extending from the first opening into the second opening, a contact plate mounted between sheets of the laminated structure and extending into the second opening, and an impedance element electrically connected between the contact plate and the contact member.

8. An electrical organ comprising, in combination, a plurality of electrical generators having frequencies in the audio range respectively corresponding to successive notes of a musical scale, an electroacoustic transducer having an input for electrical signals, a first keyboard and a second keyboard disposed in a common plane adjacent to each other, a first electrical switch mechanically coupled to each key of the first keyboard and the second keyboard, each of the first switches being normally open and electrically connected between the input of the electroacoustic transducer and one of the tone generators, a second switch and a third switch mechanically ganged to each first switch associate with a key of the first keyboard, the second and third switches being normally open and having two terminals, a manually actuatable electrical switch assembly including a first and a second section mechanically ganged together, the first section having a first terminal connected to the input of the electroacoustic transducer and a second terminal connected to one terminal of each second switch, the other terminal of each second switch being electrically connected to two tone generators different than the tone generator connected to the first switch associated with the same key of the first keyboard, said three tone generators associated with each key of the first keyboard having frequencies corresponding to the notes of a musical chord, a frequency divider having an output terminal coupled to the electroacoustic transducer and an input terminal connected to one terminal of the second section of the manually actuatable electrical switch assembly, the other terminal of said second switch being electrically connected to one terminal of each of the third switches, the other terminal of each of the third switches being electrically connected to the same tone generator as the first switch ganged to said third switch.

9. A switch comprising a plurality of sheets of insulating material, said sheets being secured together to form a laminated structure, said laminated structure having an opening extending therethrough, an electrically conducting bar disposed between two sheets of insulating material and extending across the opening, an elongated contact member having one end mounted between two sheets of insulating material and the other end confronting the conducting bar, said contact member being constructed of resilient electrically conducting material, and an actuation member movably mounted to abut the contact member between the two ends thereof and move the contact member relative to the electrically conducting bar.

10. A switch assembly comprising a plurality of sheets of electrically insulating material, means for assembling said sheets into a laminated structure, said laminated structure having an opening extending therethrough, a first electrically conducting bar disposed between two abutting sheets and a second electrically conducting bar disposed between another two abutting sheets, said bars being parallel to each other and extending through the opening in the laminated structure, a first elongated contact member mounted at one end between two abutting sheets generally normal to the first bar and extending to confront the first bar at the other end thereof, a second elongated contact member mounted at one end between another two sheets normal to the second bar and extending

to confront the second bar at the other end thereof, said first and second contact members being of resilient electrically conducting material, and an actuator member movably mounted to simultaneously engage and move the first and second contact members relative to the first and second bars.

11. A switch assembly comprising a plurality of sheets of electrically insulating material, means for assembling said sheets into a laminated structure, said laminated structure having an opening extending therethrough, a first electrically conducting bar disposed between two abutting sheets, a second electrically conducting bar disposed between two different abutting sheets, said bars being parallel to each other and extending through the opening in the laminated structure, a first elongated contact member mounted at one end between two abutting sheets generally normal to the first bar and extending to confront the first bar at the other end thereof, a second elongated contact member mounted at one end between another two sheets normal to the second bar and extending to confront the second bar at the other end thereof, said second contact member having an aperture therein, said first and second contact members being of resilient electrically conducting material, and an actuator member movably mounted to simultaneously engage and move the first and second contact members relative to the first and second bars, said actuator having a first portion of smaller cross-section than the aperture in the second contact member disposed within said aperture and a second section of larger cross-section than said aperture, said first section terminating in abutment with the first contact member and said second section terminating in abutment with the second contact member.

12. A switch comprising a plurality of sheets of insulating material, said sheets being secured together to form a laminated structure, said laminated structure having a first opening extending therethrough and a second opening extending therethrough spaced from the first opening, said first and second openings forming a bar portion therebetween, an electrically conducting bar disposed between two sheets of insulating material and extending across the first opening at a distance from the bar portion, an elongated contact member having one end mounted between two sheets of insulating material in the bar portion of the laminated structure and the other end confronting the conducting bar, said contact member being constructed of resilient conducting material, a contact plate disposed between two sheets of the laminated structure and terminating within the second opening, an impedance element having wire terminals mounted on the plate and contact member within the second opening, and an actuation member movably mounted to abut the contact member between the two ends thereof and move the contact member relative to the electrically conducting bar.

13. A switch assembly comprising, in combination, a plurality of sheets of electrically insulating material, means for assembling said sheets into a laminated structure, said laminated structure having a first plurality of aligned openings spaced from a second plurality of aligned openings forming a first longitudinal bar portion between the first group of openings and the second group of openings and a plurality of lateral bar portions extending normally from the first bar portion, a first electrically conducting bar disposed between two abutting sheets parallel to the bar portion, and a second electrically conducting bar disposed between another two abutting sheets parallel to the first electrically conducting bar and on the same plane normal to the sheets as the first bar, said bars extending through the first group of openings in the laminated structure, a first elongated contact member disposed in each of the openings and mounted at one end between another two sheets in the first bar portion, said first contact members being normal to the first bar and extending to confront the first bar at the other ends, a second elongated contact member disposed in each of the openings and

mounted at one end between two different sheets in the first bar portion of the laminated structure, said second contact members being normal to the second bar and extending to confront the second bar at the other ends, said second contact members each having an aperture therein, said first and second contact members being of resilient electrically conducting material, an actuator member having a first portion of smaller cross section than the aperture in the second contact member disposed within the aperture of each second contact member, each actuator member having a second section of larger cross section on said aperture, said first section terminating in abutment with the confronting first contact member and said second section terminating in abutment with the

second contact member, an electrically conducting plate extending into the second opening confronting each contact member, and an electrical impedance mounted between each contact member and one of the plates.
